UNITED STATES PATENT OFFICE.

PERRY BROWN, OF CORAOPOLIS, PENNSYLVANIA.

LID FOR JOURNAL-BOXES.

1,156,880.

Specification of Letters Patent. Patented Oct. 19, 1915.

Application filed December 21, 1911. Serial No. 667,246.

To all whom it may concern:

Be it known that I, PERRY BROWN, a citizen of the United States of America, and a resident of Coraopolis, in the county of Allegheny and State of Pennsylvania, have invented certain new and useful Improvements in Lids for Journal-Boxes, of which the following is a specification.

This invention relates to improvements in 10 lids for journal boxes and the object of my invention is to provide a lid which has spring actuated means to hold it in either the opened or closed positions and also with a gravity operating bolt which will 15 lock it in closed position, in such a manner that it will be impossible for the waste on the inside to force the lid open.

Other features of construction will be hereinafter described and illustrated and 20 the invention therefore consists in the lid shown in its preferable embodiment in the drawings forming part hereof and as will be hereinafter pointed out in the appended claims.

25 In the drawings: Figure 1 is a perspective view of a journal box having a lid thereon made in accordance with my invention. Fig. 2 is a vertical central section of part of a box having my invention applied thereto, 30 the lid being shown in closed position in full lines and in open position in dotted lines. Fig. 3 is a perspective view of some of the parts detached in order to more clearly show the construction. Figs. 4, 5 35 and 6 are details.

Referring now to the details of the drawings by numerals: 1 designates a journal box which may be made of any desired construction but the one illustrated in the drawings 40 is constructed on the Master Car Builders' lines. In other words, the upper part of the box has integrally cast therewith the two bearings 3 and 4 connected by a web 5 having its upper surface 6 and its vertical 45 surface 7 substantially flat to coöperate with the spring usually employed in the common form of lid. The bearings 3 and 4 are provided with an opening 8 through which passes the pin forming the pivot for the lid. The construction so far described forms 50 no part of my present invention but is illustrated as my lid is constructed to work on

boxes having the bearings 3 and 4 just described.

My lid is designated by the character 10 55 and it has formed, preferably integrally therewith, a semi-cylindrical hood 12 whose outer ends are provided with annular lugs or bearings 14 and 16, each of which is provided with an opening 18 which openings 18 60 are directly in line with the openings 8 in the bearings 3 and 4 so that a hinge pin 21 may be inserted through all of the openings 8 and 18 and thus hinge the lid 10 to the box 1. 65

The semi-cylindrical hood 12 hereinbefore referred to not only forms a connection between the annular lugs or bearings 14 and 16 but it also forms a housing to cover the members 3, 4 and 5, as will be seen in Figs. 70 1 and 2. And its upper end is provided with a cam 20 as illustrated in Figs. 1, 2 and 3 which is adapted to form part of the means for holding the lid in position. Co-acting with this cam is a spring actuated 75 plunger 24 whose smaller end projects out of an opening formed in the front of a detachable casing 26, the plunger being held in its outer position shown in full lines in Fig. 2 by means of a spring 28 working between 80 said plunger and the back wall of the casing 26. The construction is such that the spring 28 pushes the plunger against the cam 20 so that when the parts are in the position shown in full lines in Fig. 2, the plunger is 85 pressed against the rear side of the cam 20 and holds the lid in its closed position, for any effort to raise the lid is resisted by the spring 28. However, when sufficient upward pressure is exerted on the lid 1, the 90 cam 20 forces the plunger within its casing, against the tension of the spring 28, and when the lid is moved to the position shown in dotted lines in Fig. 2, the plunger rests upon the longer surface of the cam 20 and 95 holds said lid in the position shown in dotted lines in said Fig. 2.

In order that the casing 26 may be readily secured to the journal boxes, I form on or secure to the casting forming the box, a 100 dove-tail wedge 30 provided at its smaller end with a notched member 32. The bottom of the casing 26 is provided with a dove-tail recess to fit over the dove-tail

wedge 30, as seen in Figs. 2 and 4. The casing 26 is preferably formed of a malleable casting, and the end through which the notched member 32 projects is provided with 5 a lug 34 which, after the casing 26 has been placed in position, may be tapped with a hammer so that the free end of the lug 34 enters one of the notches to lock the casing in position.

16 The bottom of my lid is provided with a sliding bolt 40, the lid itself being provided with a casing 42 on its under side to form a housing for said bolt. Thus the bolt is entirely inclosed and to limit its motion 15 within the pocket formed by the casing 42, I provide on the exterior of the lid a lug 44 having two lips 46 and between these lips is formed an opening through which a pin 48 is inserted, the lower end of the pin passing 20 through a slot 50 in the sliding bolt 40, this pin 48 and its slot 50 thereby limiting the movement of the sliding bolt 40 within its casing 42. The upper end of the pin 48 is formed with round edges so that after the 25 pin is inserted in position, the lips 46 may be hammered toward each other so as to co-act with the rounded end of the pin 48 and rivet the same in place. The lower end of the sliding bolt 40 is provided with a 30 flange 52 which may be engaged by the lever of the inspector and oilers to lift the sliding bolt so that the lid may be opened. The lower wall of the opening to be closed by the lid 10 is formed with two flanges 54 and 35 56 between which the locking flange 58 of the bolt drops when said bolt is in the locking position shown in Fig. 2. The inner flange 56 is provided with one or more perforations 60 through which any oil which 40 leaks over the top of the flange 56 may pass back into the box. It will thus be seen that I have provided a lock which will be self-acting whenever the lid is closed.

It will be noticed that the bottom wall 45 of the casing 42, through which the sliding bolt 40 projects, is, when the lid is in the closed position shown in Fig. 2, directly over the flange 56 and said bottom wall, which I will designate as 51, and said flange 50 56 extend the entire width of the box. The flange 56 is also continued up the insides of the box as indicated at 59 in Fig. 2; the lid being provided with similar flanges 61 which fit within the walls forming 55 the opening of the box and close against said side flange 59.

From an inspection of my drawings, it will be seen that I have invented a simple form of lid for journal boxes which is held 60 in either closed or opened position by means of a spring pressed plunger, and also one in which a gravity operating latch operates to hold or lock the lid in its closed position so that no matter how great the pressure 65 of the waste against the inside of the lid,

said lid cannot be forced open. At the same time the inspector or oiler needs only to place the end of his waste hook under the flange 52 of the sliding bolt and pull upwardly, whereupon the bolt will slide upward within its casing 42 to the limit of the slot 50 until its locking flange 58 is free of the flange 54 forming the bottom wall of the box opening. As the operator continues to draw upward on his waste hook, the same movement which draws upward the sliding bolt 40 also opens the lid to the position shown in dotted lines in Fig. 2 so that the box may be properly inspected and given such attention as it needs. 70 75 80

What I claim as my invention is:

1. In a journal box in combination with bearings on the upper part thereof, a lid having its upper portion hinged to said bearings, said upper portion having a cam 85 projecting therefrom with two cam faces substantially at right angles to each other, and said box having a spring pressed plunger located in working relation to said cam adapted to project against one portion of 90 said cam to hold the lid open, the other part of said cam slightly overhanging said plunger when the lid is closed whereby a lock is formed.

2. In a journal box and in combination 95 with bearings on the upper part thereof, a lid having its upper portion hinged to said bearings, said upper portion having a cam projecting rearwardly, said box having a wedge shaped member, and a casing having a recess to fit over said wedge shaped member, and a spring pressed plunger within said casing working against said cam to hold the lid in position. 100

3. In a journal box and in combination 105 with bearings on the upper part thereof, a lid having its upper portion hinged to said bearings, said upper portion having a cam projecting rearwardly, said box having a wedge shaped member having notches therein, and a casing having a recess to fit over 110 said wedge shaped member, said casing having a member adapted to be moved into said notches to lock the casing in position, and a spring pressed plunger within said 115 casing working against said cam to hold the lid in position.

4. In a journal box and in combination 120 with bearings on the upper part thereof, a lid having its upper portion formed with two lugs or bearings connected by a hood, a pin passing through the bearings of said lid and said box and hinging the lid to the box, the aforesaid hood protecting the parts and having a cam projecting rearwardly, 125 said box having a spring pressed plunger working against said cam to hold the lid in position.

5. In a journal box, a lid, and a device 130 for holding the same in position comprising

a casing, a plunger working therethrough, the box having a wedge shaped member with notches therein and the casing having a recess within which said wedge shaped member fits, and the casing having a member adapted to be moved into one of said notches to lock the casing in position.

Copies of this patent may be obtained for five cents each, by addressing the "Commissioner of Patents.
Washington, D. C."

In testimony whereof I affix my signature
in presence of two witnesses.

PERRY BROWN.
